UNITED STATES PATENT OFFICE.

JAMES W. SCOTT, OF FALCON, COLORADO.

POTATO DIGGER.

Application filed January 3, 1920. Serial No. 349,176.

To all whom it may concern:

Be it known that I, JAMES W. SCOTT, a citizen of the United States, and a resident of Falcon, in the county of El Paso and 5 State of Colorado, have invented a new and Improved Potato Digger, of which the following is a full, clear, and exact description.

This invention relates to potato diggers and more particularly to improvements on 10 the potato-digging machine as illustrated and described in my Letters Patent No. 396,433, issued January 22, 1889.

An object of my invention is to provide 15 novel and simplified improvements combined with the above-identified potato digger to produce an efficient digging machine capable of operating at comparatively high speed and which will do greatly improved work over the old machine.

20 Among other things, the older potato-digging machine embodied a plow which unearthed potatoes and threw them back on a vibrating carrier. The plow was non-adjustable, likewise there was no arrangement 25 for adjusting the vibrating amplitude of the carrier.

It is fitting, therefore, that the primary 30 object of this invention is to provide means for regulating the amplitude of motion of the vibrating potato carrier in order to increase 35 the working capacity of the machine to the end that it may do more work and better work.

With the above principal object and 35 others in view, the invention has relation to the combination and arrangement of parts as set forth in the several claims defining my invention, and one particular embodiment of which is described in the following 40 specification and illustrated in the accompanying drawings.

Figure 1 shows a side elevation of the 45 potato digger; Figure 2 shows a plan view thereof; and Figure 3 shows a rear elevation of the digging machine.

Figure 4 illustrates a sectional view taken on the line 4-4 of Figure 2; and Figure 5 illustrates a sectional view taken on the line 5-5 of Figure 4.

50 Figure 6 illustrates a sectional view taken on the line 6-6 of Figure 1 to illustrate a ratchet-drive mechanism; and Figure 7 illustrates a sectional view developed on the line 7-7 of Figure 6.

55 Figure 8 shows a face view of a driving crank having adjustable means for varying

the throw of the crank; and Figure 9 illustrates a sectional view taken on the line 9-9 of Figure 8.

Figure 10 shows the manner of connecting 60 parts employed in the construction of the vibrating potato carrier. Figures 11, 12 and 13 show perspective views of various forms of stirring means employed for throwing the dirt and potatoes back on the carrier. 65

A potato digger constructed in accordance with the plans of my invention employs an appropriate form of horse-drawn farm tool having traction ground wheels. There is provided a plow carried on pivoted 70 plow beams, and means associated with the pivoted plow beams for regulating the depth of the plow. There is also provided a vibrating or shaking potato carrier which receives the dirt and potatoes unearthed by 75 the plow, and it functions to shake the dirt therefrom and drop the potatoes in the rear of the machine on top of the ground for the convenience of the gatherers, who may then pick the potatoes from the ground 80 and sack them for shipment. A feature of my invention resides in the adjustable arrangement for varying the distance of swing or amplitude of the vibrating carrier. An elevating plate is mounted for augmenting 85 the removal of dirt and potatoes from the plow, and operates to throw the potatoes back on the vibrating carrier.

In presenting a more detailed description 90 of my invention, there is employed a suitable form of carriage upon which the potato-digging parts are mounted. The carriage has a frame 18 made in the shape of a yoke, the closed end of which is mounted forward, and a tongue 19 is mounted on the 95 frame to draw the machine along the row. An axle 20 is carried on the frame and has the ground traction wheels 21 journaled thereon. Braces 22 are applied to the frame 18 to strengthen it and to make the rear open end 100 rigid, and to provide a support for parts, as later described.

A plow beam 26 is pivoted at 27 on each side of the frame 18, and on the lower ends of the plow beams there is mounted a plow 105 28 which passes underneath the surface of the ground to unearth potatoes and the like. The plow is rigidly secured to the lower ends of the plow beams and held in service position between the beams in line with the 110 row being plowed. The upper forward end of the pivoted plow beam 26 is provided

with a gear sector 29. A shaft 30 is journaled across the frame 18 with a gear sector 31 fixed to each end of the shaft and engaging with the gear sectors 29 on the plow beams. A hand lever 32 is fixed on the shaft 30 and stands vertical in operating position adjacent to and convenient with the operator's seat 33. It is seen how the operator may shift the lever back and forth to 10 rotate the gear sector 31, which impresses rotation to the sector 29 and changes the position of the plow 28. The operator is able to vary the angle of the plow with respect to the horizontal in order to counteract any tendency of the draft on the tongue to pull the plow out of the ground. The lever 32 is employed for this purpose, that is to say, it is employed to vary the cutting angle of the plow.

20 Each ground traction wheel has fixed thereto a drive sprocket 37. A crank shaft 38 is journaled transversely of the frame and has fixed on each outer end a sprocket 39; and a chain 40 is confined on the pairs 25 of sprockets to drive the crank shaft 38 from the traction wheels 21. As the machine proceeds along the row, the crank shaft 38 is rotated, which reciprocates a pair of bars 41 carried on the cranks 42. The 30 lower ends of the bars 41 carry an elevating plate 42^a which is subjected to a swinging and reciprocating motion imparted by the cranks 42. The upper ends of the bars 41 have fixed thereto bars 43. A cross member 44 is supported in rigid position and has links 45 loosely connected thereto. The 35 other ends of the links 45 are attached to the upper ends of the bars 43. The links 45 serve to hold the upper ends of the bars 43 in approximately fixed position while the 40 lower ends of the bars 41 undergo a back-and-forth or a reciprocating motion. A plurality of holes are made in the bars 43 to permit vertical adjustment of the links 45 in order to change the vertical adjustment 45 of the bars 43. The rotating crank shaft 38 subjects the elevating plate 42^a to a back-and-forth motion which sweeps rearwardly the dirt and potatoes from the back of the 50 plow.

The traction wheels 21 carry internal gears 47. A transverse drive shaft 48 is journaled on the frame 18, and a drive pinion 49 is fixed to each end of the shaft 48 and meshes with the internal gears 47 of the two traction wheels. A bevel gear 50 is loosely confined on the shaft 48 and has a clutch face 51. A sliding clutch 52 is carried on the shaft 48 and fixed to rotate with 55 the shaft, and when engaged with the clutch 51 there is established a driving relation between the shaft 48 and the bevel gear 50. A driven shaft 53 is journaled in supports and has a bevel gear 54 fixed to the front end 60 engaging with the driving gear 50.

The rear end of the shaft 53 is provided with a crank disk 55 fixed thereto and having adjustable means related with the crank disk to change the radius of the crank throw. A radius arm 56 is pivoted on the 70 crank disk 55 through the agency of a pin or bolt 57. A slot 58 is cut in the crank disk 55 concentric with the bolt 57, and a clamp screw 59 is confined in the slot 58, being passed through the radius arm and a 75 connecting rod 60. A bushing may be employed to provide an adequate bearing surface and coupled relation between the connecting rod 60 and the radius arm 56. By binding the clamp screw 59 the radius arm 80 85 and connecting rod 60 are fixed positively in relation to the crank disk 55. By loosening the clamp screw 59, the radius arm 56 may be swung about the center 57 and clamped in any position within the slot 58. This feature enables the operator to vary the radius of crank throw imparted to the connecting rod 60 from the crank disk 55. While the drawings show one practical embodiment of means for changing the radius 90 of the crank throw on the crank disk 55, it is pointed out that other suitable designs may be used to good effect, and the use of which are contemplated under the rights of this invention.

95 A bracket 64 is secured to the rear end of one side of the frame 18 and supports a lever 65 pivoted at 66 to the bracket. The link 67 is pivotally hung on the lower end of the lever 65. The link 67 is adapted to undergo 100 a lateral motion, and is also capable of independent back-and-forth motion, or motion longitudinal with the direction of travel of the machine down the row plowed.

105 A plurality of bars 68 are supported on the cross-bar 69 with the rear ends flared outwardly, and with the forward ends resting on another crossbar 70. The crossbars 70 may be attached to the bars or ribs 68 to hold the structural framework together, and the bar 70 may be confined under the rear edge of the plow 28. The ends of the crossbar 69 project beyond the ribs and framework of the vibrating carrier, said carrier comprising the parts 68 and 69. A 110 link 71 is attached to a bracket 72 fixed to the frame of the machine and supports one side of the vibrating carrier 68; while the other end of the bar 69 is attached to the lower end of the link 67 to support the other side of the carrier. In this way the carrier is supported in approximately horizontal 115 position between the two links to ride behind the plow 28.

120 A description will now be given of some of the detail parts of the machine which make for efficiency and practical operation. In Figure 6 there is illustrated a cross-sectional view taken on the line 6—6 of Figure 1, and Figure 7 is a detail view taken on the 125 130

line 7-7 in the Figure 6. An internal ratchet wheel 73 is fixed to the crank shaft 38. The sprocket 39, as previously mentioned, is freely mounted on the shaft adjacent the internal ratchet wheel 73. A pawl 74 is pivoted on the face of the sprocket 39 and confined in the ratchet wheel 73 with a spring to hold the pawl in positive engagement with the ratchet teeth. It is seen how the potato digger when driven forward drives the crank shaft 38 through the agency of the pawl 74 and ratchet wheel 73; but, however, when the machine is backed up for any reason, the ratchet and pawl mechanism disengage when the pawl moves forward away from the ratchet teeth. This arrangement acts to allow the sprocket 39 to move loosely on the crank shaft 38 without revolving the crank shaft. It is usually necessary to provide this mechanism in order to avoid operating the elevating plate 42^a when the machine is backed up for short distances in the field, as it is undesirable to reverse the operation of the elevating plate.

In order to advance the state of the art to a point of marked perfection, and in order to disclose alternate means for elevating or throwing the plowed earth and potatoes from the plow to the rear upon the vibrating carrier, I show several different forms of teeth 76 which may be bolted to the lower ends of the bars 41 when it is more practical to use elevating means of less capacity than that shown in the Figure 3. The teeth 76 act to stir the ground and help move it back from the plow, and also serve to break up the earth, which causes it to drop through the carrier bars 68 faster than it would otherwise do where the breaking teeth 76 are not employed. It is practical to employ the elevating plate 42^a for throwing back the earth and potatoes where the potato digger is operating in comparatively soft soil where few clods and hard lumps prevail. The breaking teeth 76 may be used to better advantage than the plate 42^a where the potato digger is working in hard, cloddy ground.

In Figure 11 there is shown one preferable means of connecting the forward end of the bars 68 to the cross member 70. It is usually more practical to connect the two outside bars 68 to the crossbar 70 by providing a loose connection, which consists in inserting the forward hooked end 82 through holes made in the bar. This provides a partly flexible connection between the bars 68 and 70 to permit adjustment and to avoid binding of the vibrating carrier when it is in operation.

A shield 83 has an arm or bracket 84 which reaches up and bolts to the frame of the carriage. The shield 83 is held in parallel relation on each side of the vibrating carrier 68, which serves to prevent the potatoes from

being thrown to one side of the machine due to the high-speed lateral-swinging motion of the carrier. When the potatoes are thrown to one side or the other the shield 83 catches them, which causes the potatoes to drop off the rear end of the carrier in line with the potato-digging machine. In this manner there will be no potatoes thrown upon the adjacent rows, and, hence, none will be lost or damaged through the plowing operation on the succeeding rows.

In the plowing operation, the performance of the machine is such that the plow 28 up-earths the potatoes and considerable soil therewith. The elevating plate 42^a lifts upwardly and travels forwardly to drop down in front of the unearthed materials. The plate then moves rearwardly under the direct action of the crank shaft 38 to throw the unearthed materials upon the vibrating carrier 68. The crank disk 55 subjects the vibrating carrier to lateral swinging motion, simulating a high-speed vibrating action, which continually shakes the dirt from the unearthed potatoes. As the plow proceeds along the row the potatoes gradually drop off the rear end of the carrier, which leaves the potatoes on top of the plowed soil.

A paramount feature of my invention resides in the adjustable radius arm 56 on the crank disk, which enables the operator to adjustably vary the motion of crank throw generated in the crank disk 55. In soft, well mulched soil it is unnecessary to vibrate the carrier 68 to any great extent since the soft soil feeds very fast through the carrier. However, in cloddy and hard ground it is necessary to change the position of the radius arm 56 so as to impart a relatively long crank throw to the connecting rod 60 in order to subject the carrier to oscillations of considerable amplitude. This action on the part of the carrier violently rolls and shakes the large clods, breaking them up, thus leaving comparatively smooth, level and well-broken soil behind the plow.

The operator will regulate the depth of the plow 28 in accordance with the growth conditions of the potatoes being dug. Where the potatoes have rooted quite deeply, it is necessary to plow deeper; to this end the machine is provided with the pivoted plow beam 26 and adjusting lever 32.

It is pointed out that the carrier 68 is capable of a back-and-forth swinging motion on the links 71 and 67 which permits the carrier to move back in order to ride over any obstructions, such as rocks or stumps, in the line of travel of the machine.

This form of potato-digging machine will harvest potatoes faster than can ordinarily be done by hand, and, furthermore, it leaves them on top of the ground to be dry cured prior to sacking the potatoes for the market.

Having thus described my invention, I de-

sire to claim as new and secure by Letters Patent:

1. In a potato-digging machine, a carriage, a plow blade for unearthing the potatoes, a vibrating carrier for receiving the unearthing potatoes and for separating the potatoes from the earth, and means for adjusting the amplitude of vibration of the carrier.
2. In a potato-digging machine, a carriage, a plow blade to unearth the potatoes, a vibrating carrier mounted on the carriage, a drive shaft for vibrating the carrier, and

an adjustable radius arm arranged to change the amplitude of the vibration of the carrier. 15

3. In a potato digging machine, a carriage, a plow to unearth the potatoes, a vibrating carrier mounted on the carriage, a driven shaft, a disk on one end of the shaft and having a curved slot, an arm pivoted to the disk adjacent the slot thereof, a bolt carried by the arm and adjustably secured in said slot, a rod connected with said arm, and means connecting the rod with said carrier.

JAMES W. SCOTT.
